UNITED STATES PATENT OFFICE.

FREDERICK ROUNSVILLE PAYNE AND DAVID WELLS PAYNE, OF ELMIRA, NEW YORK.

AUTOMATIC STARTING DEVICE FOR INTERNAL-COMBUSTION ENGINES.

1,115,562.

Specification of Letters Patent.

Patented Nov. 3, 1914.

Application filed July 28, 1911. Serial No. 641,136.

To all whom it may concern:

Be it known that we, FREDERICK R. PAYNE and DAVID W. PAYNE, citizens of the United States, residing at Elmira, in the county of Chemung and State of New York, have invented a new and useful Improvement in Automatic Starting Devices for Internal-Combustion Engines, of which the following is a specification.

10 This invention relates to an automatic starting device for internal combustion engines, and while not limited to use in connection with automobiles, it is especially designed to be applied to that type of engines usually used in connection with motor vehicles, and one of the main objects of the invention is to avoid the necessity of cranking a motor vehicle as at present, in order to start the engine.

20 Briefly stated the object of the invention is to operate selectively the valves of an internal combustion engine, at other times than those at which they would be normally operated, by other means than shifting the 25 cams, or cam shaft longitudinally and thereby admitting a charge of explosive gas under pressure to the selected cylinder, exploding said charge, and thus starting the engine without cranking.

30 A further object of the invention, and one which is incidental to the construction employed, is that of converting either for a few moments or for a considerable duration of time, a cylinder of the engine into an air 35 compressor or vacuum device, the said cylinder being reconverted into a power cylinder when desired, thereby enabling an automobile engine to be readily employed for the purpose of providing compressed air or 40 vacuum which may be used for any suitable purpose, or to perform any work conveniently done by air pressure or vacuum.

The invention consists in the novel features of construction hereinafter set forth, 45 pointed out in the claims and shown in the accompanying drawings, in which:

Figure 1, is a side elevation of a four cylinder four cycle engine of a type now in use, and having our device applied thereto. 50 Fig. 2, is a plan view of Fig. 1, parts being broken away. Fig. 3, is a horizontal section taken through the engine base and

showing the drive shaft, cam shaft and our valve lifting device, with portions of the manually operated connection. Fig. 4, is 55 a section through the automatic pressure regulating valve, and showing the automatic circuit breaker in the sparking circuit of the compression cylinder. Fig. 5 is a vertical section through one of the engine cylinders, one of the valve lifting devices being shown in dotted lines. Fig. 6, is an enlarged detail elevation of a pair of cams and a cam roller. Fig. 7, is a similar view at right angles to Fig. 6. Fig. 8 is a detailed 60 sectional view illustrating the construction and arrangement of a valve adapted to admit gas from the compression tank to suitable pipes and thence to the engine cylinder. Fig. 9, is a diagrammatic view illustrating 70 the position of the cams at various phases of the engine cycle, with the engine running counter clock wise. Fig. 10, is a vertical section through an engine cylinder illustrating a modified form of construction. 75 Fig. 11, is an irregular horizontal section showing in plan certain gearing shown in elevation in Fig. 10. Fig. 12 is a partial plan view illustrating a slight modification 80 in the arrangement of certain pipes. Fig. 13 is a front elevation of the parts shown in Fig. 12.

In the drawings, 1, represents a four cycle engine although it will of course be understood that the device may be modified 85 in order to adapt it for use with other engines than those of the four cycle type.

The useful fly wheel 2, is mounted upon the engine shaft 3, and as these parts are those in common use, no detailed description 90 of them is thought necessary. To one side of the engine is arranged a tank 4, designed to contain the compressed gas, by means of which the starting operation is accomplished. At one end and adjacent the upper portion of the engine is a valve casing 5, which is connected to the tank 4, by means of a pipe 6, said casing also being connected to an exhaust pipe 7, common to all of the cylinders, and said casing has communication 100 with the engine cylinders through a pipe 8, which normally forms a branch of the exhaust pipe. The tank 4, is also connected by means of a pipe 9, with a valve casing 10,

located centrally with respect to the front of the engine, said valve casing having communication through a pipe 11, with a carbureter 13, and communicating with the engine cylinders are suitable pipes 12.

Referring in detail to the construction of the valves contained in these casings, it will be noted from Fig. 4, that the casing 5, opens directly through the rear side into the 10 pipe 8, and is provided with valve seats 14 and 14^a, in which work respectively valves 16 and 17, said valves being fixed upon a common stem 15, valve 16 having a larger area than 17, but we do not limit ourselves 15 to this construction of valve. These valves respectively regulate communication between the pipe 8 and the pipe 6, leading to the tank 4, and the common exhaust pipe 7.

It will be noted that the valves are so 20 positioned upon the valve stem that when one of the said valves is closed the other is open, and the valve 16 is normally held closed by pressure of gas or air in the tank 4, and 17 is closed by the pressure of a suitable spring 22, which is coiled about the 25 projecting portion of the stem 15. An arm 18, carries the contact points 19, of a switch, or circuit breaker, in the sparking circuit of the compression cylinder, and the valve stem 30 15 carries a rod 20, upon the end of which is mounted a cone 21, which, when the valve 16, is engaged with the seat 14, closes the space between the contacts 19, the circuit being broken at this place upon outward 35 movement of the valve stem 15, and the opening of the valve 16, and the closing of the valve 17. The pipe 9, leading from the tank 4, to the valve casing 10, opens into the lower portion of said casing, and the 40 pipes 11 and 12, open into the upper portion, a valve seat 23, Fig. 8, being formed co-operative with a valve 24 to cut off communication between the pipes 11 and 12, and the pipe 9. This valve is provided with 45 a stem 25, the upper portion of which is provided with a coil spring 26, which normally holds the valve in its seat, the said upper portion of the stem being adapted to work in a suitable guideway formed in a 50 cap 27, which closes the upper end of the casing 10. The lower portion of this stem projects downwardly below the casing and is engaged by a finger 28, carried by an operating lever 29. Explosive gas under 55 pressure from tank 4, is admitted to that cylinder or cylinders of any group, which in a normally operating engine would have been the one wherein an explosion should next occur. The selection of this cylinder 60 may be automatically accomplished in a variety of ways and a preferred form for securing this result is as follows: The cam shaft 30, Fig. 3, arranged parallel to the drive shaft 3, is provided with the usual 65 admission cams 31, also with suitable ex-

haust cams 39, and adjacent each of the admission cams 31, and working in unison therewith is a supplemental cam 32.

In Fig. 9, we have shown in diagrammatic form the position occupied by the cam 31, during various phases of the operation of the engine when running counter clockwise, the nose of the cam occupying the position at *a* at the beginning of admission, at *d* at beginning of compression, at *c* during 70 explosion, and at *b* at beginning of exhaust, these phases taking place in the cylinder beneath which said cam is located. The approximate relative position of the nose of the cam 32, to that of the cam 31, is indicated in Fig. 6, when the engine is running anti-clockwise, and this position is always maintained. It will also be noted that the nose of the cam 32, does not project beyond the hub of the cam 31, and while a cam 80 roller 33, with which the cams coöperate overlaps both the cam 31, and its adjacent cam 32, the latter cannot by itself lift the valve stem 34, of the cylinder valve 35. To lift the stem 34, and thus open 90 the valve 35, independent of the action of the cam 31, we place a shaft 36, parallel to the cam shaft 30, said shaft being rocked by a suitable arm 37, the arm being controlled by the operator from the 95 seat of the vehicle as will hereafter be described. The shaft 36, carries upwardly extending arms 37, equal in number to the engine cylinders and these arms carry spring hinged fingers 38, which are in alinement 100 with the cams 32. Upon the rocking of the shaft 36, the fingers 38, will engage the rollers 33, and will pass between said rollers and the cams 32. The nose of cam 32, which first engages one of the fingers will lift the 105 finger engaged, thereby lifting one of the stems 34. It will be obvious that by reason of the relative position existing between the cams 32, and 31, the stem 34, which will be lifted, will be that one operating in the 110 cylinder in which the next explosion should take place. It will also be obvious that similar supplemental cams 39^a, may be placed adjacent the exhaust cams, and similar fingers, not shown, may operate in connection 115 with the exhaust cams in the same manner that the fingers 38 operate in connection with the admission cams, thereby opening the exhaust valve in the cylinder under compression, thereby releasing the compression, 120 in said cylinder and thus aid in starting the engine, but such arrangement is optional. It is also obvious that the fingers 38, may be inserted between cams 32, and rollers 33, by other methods.

The admission valve 35, is opened by means of the finger 38, and the valve 24, is also opened at the same time, both, by means of a suitable hand lever 41^a, arranged conveniently for the operator. This lever is 125 130

5 pivotally connected to a sliding bar 42 to which the lower end of the valve operating lever 29, is pivoted, and there is also secured to the bar 42, a bar 43, which is by a suitable system of pivoted links 44, connected to the rod 45, in turn pivotally connected to the arm 37, so that forward movement of the lever 41^a, will cause the valve 24 to lift from its seat 23, and will also cause 10 the shaft 36, to rock, thus throwing the fingers 3^a, beneath the rollers 33, Fig. 6, and between said rollers and the cam 32, thus raising the admission valve 35. The lever 41^a, is returned to its normal position after 15 being pushed forward by the spring 47, or by hand, and the engine is restored to normal working condition. We also include in the sparking circuit, a circuit breaker 46, which is arranged upon the quadrant 20 over which the hand lever 41^a, works, so that when the latch 40^a, is raised to permit movement of the lever 41^a, the sparking circuit is broken for all cylinders, and cannot be re-established until the latch 40^a has 25 been lowered by the return of lever 41^a to its normal position, and the engine placed in operating condition, thereby automatically rendering an explosion or flare back impossible, when the normal conditions are 30 interrupted.

From the above description it is thought that the operation will be clear and it may be briefly summed up as follows: The initial starting of the engine may be effected 35 either by cranking or by filling tank 4, with an explosive gas under pressure. (Note.— Hereafter when the term gas is used an explosive gas drawn from the carburetor is understood.) After this the engine is started 40 by means of the compressed gas stored in the tank 4, and which is automatically maintained in the following manner. While the engine is in operation and as soon as the pressure in tank 4, drops to or slightly 45 below that required for starting the engine, the valve 16 opens, and valve 17, closes, this immediately breaking the sparking circuit of one of the compression cylinders, by moving the cone 21, from between the contact plates or points 19. The cylinder so selected is at once converted into a compressor, and the gas drawn from the carburetor through the inlet valve is compressed in the compression cylinder and 55 passed through pipe 6, to tank 4; the cylinder from which the said compressed gas is received being at this time cut off from the common exhaust pipe 7, by the seating of the valve 17, by means of spring 22.

60 It will be understood that in order to illustrate this invention, we have shown it applied to a four cylinder, four cycle engine, and with means for converting only one cylinder into a compression cylinder, but 65 we do not wish to limit ourselves to an en-

gine having only four cylinders, nor to a construction which would connect the tank 4, with only one cylinder of the engine at a time, as more than one cylinder can be so connected if desired.

When the desired pressure is obtained, the valve 16, under pressure of the gas in tank 4, will seat itself thereby bringing the said cylinder into communication with the exhaust pipe 7, restoring the sparking circuit and re-establishing it as one of the power cylinders.

It will be understood that while we have described the manner of charging the tank 4, from the engine with an explosive gas to be utilized in starting the engine, it will be obvious that if desired, the tank may be charged by compressed air by adding a suitable air intake valve to the device between the engine cylinder and the valve casing 10. 80 Or by cutting out the tank 4, and using the intake valve above mentioned with hose attachment at intake, the cylinder may be converted into a vacuum pump. The spring 22, will serve to maintain in the tank 4, either a sufficient pressure to start the engine by the expansive force of the gas, or a lower pressure may be carried in the tank and the charge admitted therefrom into the proper cylinder and there exploded. The 85 manner by which this cylinder is automatically selected and the valve therein opened has already been explained. It will be obvious therefore that upon the forward movement of the hand lever 41^a and the opening 100 of the valve 35 in the cylinder selected, an explosive charge of compressed gas will pass from the tank 4, through the pipe 9, into the valve casing 10, and through valve 24, which has been opened by such movement of lever 41^a, and thence through one of the pipes 12, to the proper cylinder. The charge in the selected cylinder is now exploded by the ordinary sparking apparatus 105 by the proper change of the timing device 110 from its normal position, thereby starting the engine in normal operation.

To prevent impairing the explosive value of the gas in tank 4, during cold weather, a portion of the exhaust gas is taken in a 115 pipe from the common exhaust pipe 7, and carried in a coil through the tank 4, and then allowed to escape to the atmosphere, as shown by dotted lines in Figs. 1 and 2. This pipe is provided with a stop valve, between pipe 7 and tank 4, to be closed when the heating provision is not required. In extreme cold weather when the engine has not been in use means should be provided to prevent the temperature of the tank falling 120 below the desirable point to furnish an explosive mixture. This is accomplished by placing a lamp under tank 4, and providing said tank with a safety valve.

In Figs. 10 and 11, we have shown a 130

modified form of construction for opening the cylinder valve 35. In place of the gears 40 and 41, transmitting motion from the drive shaft 3, to the cam shaft 30, we place 5 on the crank or drive shaft a spur gear 48, which meshes with a gear 49, mounted loosely on the cam shaft 30. This gear engages the gear 49', mounted upon a stub shaft 51. This shaft is supported by arms 51^a, which swing freely on the cam shaft 30. On the shaft 51, is fixed a gear 52, which through an intermediate pinion 53, engages a gear 54, fixed upon the shaft 30. The relation of these gears is such that one 15 rotation of the gear 54 is produced by two rotations of the gear 48. Now if the shaft 51, be swung through the proper arc, by means of the lever 41^a, and its connection, the shaft 30, and the fixed gear wheel 54, 20 will be rotated and as gear 49 is loose on the shaft 30, but held rigidly against rotation by the gear 48, it will remain stationary when the gear 54 and the shaft 30 are rotated. The rotation of the shaft 30, causes 25 the admission cams pertaining to the cylinders on explosion stroke to open their corresponding valves, thereby gases are admitted to cylinders, through the valve 24, as previously described in connection with 30 Figs. 5 and 8. When the shaft 30, is restored to its original position by returning lever 41^a, to its running position, the cylinder is in condition to be fired as previously described.

35 The results as above described relate only to the explosion cylinder; the effect of rotation of shaft 30, upon the valves of the other cylinders, would be the same as that which would be produced in any hydro- 40 carbon engine under similar conditions and it is not deemed necessary to describe them, being fully understood by those familiar with gas engines.

What we claim is:

45 1. The combination with an internal combustion engine, of manually operated means for selecting and opening the admission valve in that cylinder in which an explosion should normally next occur without 50 moving cams or cam shaft longitudinally, and means for introducing into said selected cylinder a charge of explosive gas under pressure as and for the purpose set forth.

2. In an internal combustion engine, a 55 starting device comprising means for selecting that cylinder in which an explosion should next normally occur, means for opening the intake valve in said cylinder, a storage tank containing gas under pressure, 60 and means for bringing said storage tank into communication with the cylinder in which the valve has been opened, all said means operating in unison and simultaneously.

65 3. The combination of an internal com-

bustion engine, a starting device, a supplemental storage tank adapted to receive gas under pressure, means for automatically selecting and bringing one of the engine cylinders into communication with said tank 70 through its exhaust while the engine is running and at the same time cutting said cylinder off from the common exhaust pipe, and means for maintaining a predetermined pressure in said storage tank. 75

4. The combination with an internal combustion engine, adapted to be started by admitting gas under pressure to one of the cylinders, of a storage tank adapted to receive said gas, means for automatically cutting out one of the engine cylinders from the common exhaust while the engine is running and automatically bringing the same into communication with said tank for the purpose of maintaining a predetermined pressure, and means for automatically breaking the sparking circuit while the said cylinder and tank are in communication. 80

5. The combination with an internal combustion engine, a starting device, a storage tank adapted to receive air or gas under pressure said tank having valve controlled communication with one of the engine cylinders, said communication being normally 90 closed, the said valve automatically opening when the pressure in the storage tank falls below the predetermined amount, and automatically closing when pressure in said tank reaches said predetermined amount, 95 the opening of said valve also serving to close communication between said cylinders and the common exhaust, and also breaking the sparking circuit to said cylinder. 100

6. In an internal combustion engine, a 105 starting device, a storage tank, valve controlled communication between said storage tank and one of the engine cylinders, means for automatically cutting said cylinder out of communication with the common exhaust pipe, when the valve above 110 mentioned is opened and means for automatically cutting said cylinder out of the sparking circuit when said valve is opened as and for the purpose set forth. 115

7. The combination of an internal combustion engine, a starting device, a storage tank for gas under pressure, valve controlled communication between said tank and one of the engine cylinders, means for cutting the said cylinder out from the common exhaust pipe automatically, means for cutting said cylinder out of the sparking circuit automatically and a heating coil of pipe in said tank adapted to be heated by 120 the exploded gases, or other means as and 125 for the purpose described.

8. The combination of an internal combustion engine, a starting device, a storage tank for gas under pressure, valve con- 130

trolled communication between said tank and one of the engine cylinders, means for cutting out said cylinder from the common exhaust pipe automatically, means for cutting out said cylinder from the sparking circuit automatically, a coil of pipe in said tank adapted to be heated by passage of exhaust gases therethrough as described and a lamp arranged to heat from the exterior the contents of said tank as and for the purpose described.
